UNITED STATES PATENT OFFICE

CHARLES L. LOWMAN, OF LOS ANGELES, CALIFORNIA

GYMNASIUM APPARATUS

Application filed May 21, 1931. Serial No. 538,996.

This invention relates to gymnasium apparatus.

An object of the invention is to provide a gymnastic plinth or exercising table adapted to be used within an aquatic pool in such position that a person may be partially supported upon the table and partially floating within the water of the pool.

A further object is to provide various adjustments whereby the aquatic plinth may be mounted at any one of several possible positions in the pool, or adjusted to vary the inclination of the plinth, thereby making it possible to support only those portions of the body which it is necessary to support in order to provide the desired fixation for the particular exercise or treatment being administered to a particular body segment.

Another object is to provide means for adjusting the plinth so as to vary its position with respect to the surface of the water, whereby the person receiving treatment may be more or less nearly completely immersed, depending upon the circumstances of the particular case.

Another object is to provide an adjustable aquatic plinth as described, which is also provided with means adapted to be grasped by a hand or the hands of a person in any one of a plurality of possible positions, thereby also assisting in attaining the desired fixation and localization of muscle action.

The invention possesses other objects and advantageous features, some of which, with those enumerated, will be set forth in the following description of the invention's particular embodiment which is illustrated in the drawings accompanying and forming a part of the specification.

Referring to the drawings:

Fig. 1 is a transverse vertical sectional view taken through an aquatic pool and showing a plinth embodying the principles of the present invention operatively mounted therein.

Fig. 2 is a top plan view of the structure illustrated upon Fig. 1.

Fig. 3 is an enlarged top plan view of the upper or head end of the plinth and the sup-

porting standard upon which it is mounted. This view may be considered as a horizontal sectional view taken substantially upon the line 3—3 of Fig. 1, with the direction of view as indicated.

Fig. 4 is a view in side elevation, the direction of view being indicated by the arrow 4 of Fig. 3. Portions of the figure are broken away to reduce its length.

Fig. 5 is an enlarged transverse sectional view taken substantially upon the line 5—5 of Fig. 2, with the direction of view as indicated.

It is well known in the art to which this invention appertains that hydrogymnastics are frequently of great benefit in corrective procedure, and the present invention contemplates the provision of a piece of hydrogymnastic apparatus whereby full advantage may be taken of the benefit which may be derived from the treatment in pools of postural faults and physical handicaps.

The chief values of pool treatment and exercises are:

First, the use of water exercises allows the body to be supported in the horizontal plane without weight on the joints of spine, pelvis and legs, thus neutralizing the force of gravity in its influence on posture. Hence, the exaggerated curves of the spine in faulty postural conditions tend to straighten out into an improved alinement. The muscular activity in the form of specialized movements or gymnastic exercise can take place with greater range and force with a reduced load and in any plane. This makes for correction of faulty position and weakened muscles, and improvement of organic tone in the internal organs.

Secondly, the greater ease and freedom of movement makes this a modality suitable for use in cases of neuritic or painful conditions of joints and muscles, resulting from the fact that the limb or limbs being exercised are supported throughout their entire length as a result of the buoyancy in the water, thereby permitting the movement of the limbs without having to exert any muscular effort in supporting their weight. This allows better handling of patients suffering from such

painful joints, and allows easier development and correction of faulty and weakened muscles, these being among the benefits of this type of treatment.

5 Thirdly, pool treatment forms an excellent physiotherapeutic means for following of post-operation procedures such as tendon and joint plastic surgery after fractures and under circumstances of direct injury to the 10 back and limbs when it is desired to hasten return of function and stimulate the repair of tissue structure. In such cases the pain and muscle spasm caused merely by supporting the weight of the injured part may be so 15 intense that it is impossible for the person to perform any type of exercise or movements as early after the injury or operation as is desired. The gravity load being removed in the water, certain degrees of movement in the 20 injured part may take place much earlier in the pool than in bed or on a table, and hence the benefit derived is great.

Fourthly, the relaxation and prevention of 25 muscle spasm and pain allow a high degree of interest and enjoyment, and a decrease of apprehension and fear of movement, whereby the utmost in cooperation between the patient and supervising physician or technician is possible.

30 Although it has been realized that these benefits may be gained in the treatment of such cases, with the patient or person partially submerged, the lack of suitable equipment has seriously deterred the development 35 of this type of corrective exercise, and it is with this idea in mind that the device of the present invention has been developed.

The present invention contemplates the 40 provision of a plinth or gymnastic table, the preferred modification of which is illustrated upon the drawings and indicated in its entirety at 6. This plinth 6 comprises a board 45 7 adapted to be mounted preferably in any one of a plurality of possible positions within an aquatic pool 8.

Whereas the word "board" has been employed in order to describe the supporting surface of the plinth, it should be here explained that the word is not used in a limiting 50 sense, inasmuch as it relates neither to the material of which the supporting surface of the plinth is composed, nor to its general configuration. In its broad conception, the only 55 requirement is that a surface be provided upon which the entire trunk or merely the head and shoulders of a person may be supported, with the remainder of the person's body floating in the water 9 of the pool 8. The 60 details of construction to be described hereinbelow merely afford added convenience in the use of a plinth embodying this broad conception.

Whereas any type of support for the plinth 65 6 may be used, I prefer that a plurality of

sockets 11 be provided at various locations in the bottom 12 of the pool 8, preferably adjacent the side walls 13 thereof. The board 7 is adjustably mounted upon a standard 14 adapted to be received within any one of the 70 sockets 11, so as to position the plinth at any desired location within the pool 8. The standard 14 comprises a suitable length of tubing, preferably of non-rusting and non-corrodible material, the lower end 16 of which 75 may be secured within any one of the sockets 11 and the upper end 17 of which is provided with a cap 18 having a dependent flange or pin 19 adapted to be received within a suitable 80 socket 21 provided in a bracket 22 rigid with the associated side wall 13 above the selected socket 11. Hence the standard 14 is supported with sufficient rigidity, even though it is readily removable so as to permit its being mounted in any selected position 85 within the pool.

A collar 26 is slidably mounted upon the standard 14, this collar having a split 27 therein and a lug 28 extending therefrom on each side of the split 27, so that by tightening 90 a bolt 29 which interconnects the two lugs 28, the collar 26 may be clamped to the standard 14 at selected elevation. Preferably, a 95 slideable pin 31 is provided upon the head end of the bolt 29, so as to facilitate its manipulation. The lugs 28 also accommodate a pivot pin 32 which extends therebetween, and which also extends through a projecting lug 36 which is rigid with the upper or head end of the board 7, thereby pivotally mounting the board 7 100 upon the vertically adjustable collar 26.

105 Preferably, the board 7 comprises a metal plate 37, to which the lug 36 is rigidly secured, and a beam 38 extending therefrom in 110 position to support a plank 39, which preferably is of wood and of such length that when a patient's head rests adjacent the upper end thereof the lower end of the plank 39 will extend to a position just below the patient's hips, leaving his legs to float in the 115 water 9. The plank 39 may also be secured to the plate 37 by means of a plurality of 120 screws 41.

A second collar 42 is also slidably mounted 125 upon the standard 14, and is connected to the upper collar 26 by means of a rod or link 43, the lower end of which is rigid with the collar 42 and the upper end of which extends 130 slidably through a laterally extending boss 44 on the upper collar 26. The link 43 is provided with a plurality of holes 46 therethrough, within any one of which a locking pin 47 may be received, this pin 47 also extending through the boss 44 so as to lock the link 43 in selected position with respect to the upper collar 26, thereby rigidly retaining the two collars 26 and 42 at selected distance from each other. A brace 48 is pivoted at its lower end to the collar 42 and at its upper end to the beam 38. Consequently, the 135

angle of inclination of the board 7 with respect to the vertical may be varied by removing the pin 47, sliding the link 43 through the boss 44, and then seating the pin 47 in a different one of the holes 46.

Means are provided for assisting a person in retaining the proper position upon the board 7, by furnishing a rod 51 extending to each side of the board 7 from adjacent the upper or head end thereof. Each of these rods is pivotally mounted by means of a suitable pivot pin 52 to the plate 37, which is provided with a series of holes 53 arranged in an arc about the axis of the pivot pin 52 as a center. Hence, an anchoring pin 54 which extends through each of the rods 51, may be seated in any one of the holes 53 to retain the associated rod 51 in a selected degree of angularity with respect to the longitudinal axis of the board 7. Each of the rods 51 is provided with a plurality of pins 56 which extend through the rod 51, so as to project both above and below it. Accordingly, a person lying prone upon the board 7 may assume a comfortable position with each hand grasping that portion 58 of one of the pins 56 which extends downwards from its associated rod 51, whereas if the person is lying in supine position he may grasp those portions 59 of two pins 56 which extend upwards from their respective rods 51. Of course, the rods 51 may themselves be grasped, depending upon the particular position assumed by the person treated, and also upon whether or not his arm or arms are in either flexed or extended position. Owing to the large number of pins 56 provided at different distances from the head end of the board 7, and also to the adjustability of the rods 51, adequate fixation of the shoulder girdle may be attained with the person in substantially any position upon the plinth, and also irrespective of the existence or extent of any flexion of the patient's arm or arms.

I also prefer to provide a notch 61 in each side edge of the board 7 and suitably spaced from the head end thereof to permit the arm and/or arms of a person lying prone upon the board 7 to hang straight downwards through the notch or notches 61. This is desirable for certain arm exercises, for example, in moving the hand in a circular path with the arm held perfectly straight. However, inasmuch as the notches are employed only occasionally, I have also provided plates 62 complementary to the notches 61, and adapted to be removably retained therein by any suitable fastening means, such as a pin 63 extending through each of the plates 62 and adapted to have its inner end engaged by a spring clip 64. The plates 62 may either be completely removable from the board 7 or hinged thereto by means of hinges 66 which permit the plates 62 to be

swung downwards to hang vertically from the inner edges of the notches 61.

Operation

The person to receive treatment and/or exercise assumes his position upon, or is placed by an attendant upon the board 7, which previously has been adjusted to the proper elevation and inclination with respect to the vertical. In some cases the entire torso should be supported with arms and legs floating in the water 9. This type of support assures fixation of both the shoulder girdle and the pelvic girdle, thereby permitting exercise of the patient's legs in any desired manner. However, it may be desired to support only the patient's head and shoulders, so as to permit exercise of different muscles, both in the legs and in the trunk. Under such circumstances, the board 7 should be at a greater inclination, so that when the shoulders and head are resting upon the upper end of the board, the remainder of the body will be clear of the board and supported solely in the water 9.

Owing to the natural buoyancy of the limbs in the water, the person does not have to support their weight, and consequently the only muscular effort which he must make in order to move his limbs is that which is necessary to produce their motion against the resistance offered by the water itself, and inasmuch as this resistance is known and constant, an accurate check upon the amount of muscular effort required for any given movement, may be kept. Because of the fact that an injured limb is naturally buoyant in the water, no pain is caused a patient as a result of his having to sustain its weight. Therefore, he has a great deal more confidence, and will move the injured limb through a greater distance, effecting more complete exercise of the muscles than would be the case if it were necessary to support the weight of the limb also. In some cases only a very slight amount of muscular effort can be made by the patient, and here the attendant will move the injured limb downwards to a greater depth within the water, and then require the patient to raise the limb, which tends to float on account of its inherent buoyancy in the water, even if the patient is unable to exert any muscular effort. This has a decidedly encouraging effect upon the patient, who is able to actually see the limb performing the desired movement, apparently as a result of his own personal effort, and he is accordingly encouraged to exert greater effort on the next trial. This psychological effect upon the patient has been found to be of the utmost advantage in the treatment of patients having badly injured or deformed limbs and patients more or less subject to discouragement.

Another advantage of pool treatment lies

in the possibility of movement of the person's limb or limbs in more planes than is possible outside the pool, for example, in the case of a person requiring exercise of a leg in order to re-train the muscles following an injury or operation. Owing to the difficulty of moving the limb and the pain coincident with even slight movement thereof, when it is necessary to support the limb's entire weight the patient usually is unable to move the limb other than merely to lift it slightly from the surface upon which he is lying. However, with the limb's weight supported in the water 9, much more extensive movement of the limb is possible without discomfort to the patient, and also he can move it in substantially any direction, i. e., in a horizontal plane and also in oblique planes, as well as in a vertical plane.

Consequently, the hydrogymnastic plinth hereinabove described makes it possible to take advantage of many benefits to be gained by sub-aqueous treatment, and owing to the wide range of possible adjustments of the device substantially any set of circumstances can be satisfied so as to support the patient in exactly the right position and with the exact desired fixation in order to attain exercise of the proper muscles and/or movement of the proper joints.

It is to be understood that the details of the invention as herein disclosed, are subject to alteration within the spirit or scope of the appended claims.

35 I claim:

1. As a piece of hydrogymnastic apparatus, a submersible plinth comprising a board adapted to support the torso of a person receiving treatment, means for mounting said plinth within an aquatic pool, said board being pivoted to said supporting means for adjustment about a horizontal axis, and means for fastening said board at a selected angularity with respect to the vertical.
2. As a piece of hydrogymnastic apparatus, a submersible plinth comprising a board adapted to support the torso of a person receiving treatment, means for mounting said plinth within an aquatic pool, said board being pivoted adjacent one end to said supporting means for adjustment about a horizontal axis, means for fastening said board at a selected angularity with respect to the vertical, and means adjacent said pivoted end of said board adapted to be grasped by a hand of a person on said board.
3. As a piece of hydrogymnastic apparatus, a submersible plinth comprising a board, means for mounting said board in an inclined position in an aquatic pool to support optionally the head and shoulders or the entire torso of a person, and means adjacent the upper end of said board adapted to be grasped by a hand of a person on said board.
- 60 4. In combination with an aquatic pool, a

plinth comprising a board, means for mounting said board in an inclined position with its upper end adjacent the surface of the water of said pool, a bar extending laterally from adjacent said upper end, and a plurality of pins rigid with said bar and extending therefrom in position to be grasped by a hand of a person on said board.

5. In combination with an aquatic pool, a plinth comprising a board, means for mounting said board in an inclined position with its upper end adjacent the surface of the water of said pool, a pivotally mounted bar extending laterally from adjacent said upper end of said board and adapted to be grasped by a hand of a person on said board, and means for fastening said bar in a selected degree of angularity with the longitudinal axis of said board.

6. In combination with an aquatic pool, a plinth comprising a board, means for mounting said board in an inclined position with its upper end adjacent the surface of the water of said pool, a bar extending laterally from each side of said board adjacent the upper end thereof, and a plurality of pins rigid with each of said bars and extending therefrom in position to be grasped by the hands of a person on said board.

7. As a piece of hydrogymnastic apparatus, a submersible plinth comprising a board adapted to support the torso of a person receiving treatment, and means for mounting said plinth within an aquatic pool, said board having a notch in a side edge thereof in position to accommodate an arm of said person with said arm extending downwards through said notch.

8. As a piece of hydrogymnastic apparatus, a submersible plinth comprising a board adapted to support the torso of a person receiving treatment, means for mounting said plinth within an aquatic pool, said board having a notch in a side edge thereof in position to accommodate an arm of said person with said arm extending downwards through said notch, a plate complementary to said notch and removably receivable therein, and releasable means for fastening said plate within said notch.

9. A hydrogymnastic apparatus comprising a standard adapted to be removably mounted at its lower end in the floor of an aquatic pool, a collar slidable on said standard, means for clamping said collar in a selected position upon said standard, a board pivotally connected at one end to said collar for adjustment about a horizontal axis, and means for supporting the other end of said board with the board at a selected inclination and in fixed relation to the vertical.

10. A hydrogymnastic apparatus comprising a standard adapted to be removably mounted at its lower end in the floor of an aquatic pool, means for releasably connect-

ing the upper end of said standard to a wall of said pool, a collar slideable on said standard, means for clamping said collar in a selected position upon said standard, a board 5 pivotally connected at one end to said collar for adjustment about a horizontal axis and in fixed relation thereto, and means for supporting the other end of said board with the board at a selected inclination to the 10 vertical.

11. A hydrogymnastic apparatus comprising a standard adapted to be removably mounted at its lower end in the floor of an aquatic pool, a collar slideable on said standard, means for clamping said collar in a selected position upon said standard, a board pivotally connected at one end to said collar for adjustment about a horizontal axis and in fixed relation thereto, a second collar slideable 15 upon said standard, a brace pivoted to said second collar and to said board, a link fastened to one of said collars, and means for fastening said link to the other collar to hold 20 said board in a selected degree of angularity with the vertical.

12. As a piece of hydrogymnastic apparatus, a submersible plinth comprising a board having a plane upper surface through its entire length, means for mounting said board 25 in an inclined fixed position in an aquatic pool to support optionally the head and shoulders or the entire torso of a person on said surface while permitting the legs to float in the pool, and means mounted on said plinth 30 to be grasped for support by the hand of the person under treatment.

In testimony whereof I have signed my name to this specification.

CHARLES L. LOWMAN.
